UNITED STATES PATENT OFFICE.

REUBEN H. RICKER, OF BOSTON, MASSACHUSETTS, ASSIGNOR OF ONE-HALF
TO C. FRED. HOWE, OF SAME PLACE.

SAFE FOR MILK-CANS, &c.

SPECIFICATION forming part of Letters Patent No. 439,605, dated October 28, 1890.
Application filed March 26, 1890. Serial No. 345,437. (No model.)

To all whom it may concern:

Be it known that I, REUBEN H. RICKER, of Boston, in the county of Suffolk and State of Massachusetts, have invented a new and useful Improvement in Safes for Milk-Cans and other Articles, of which the following, taken in connection with the accompanying drawings, is a specification.

The object of my invention is to so construct a safe or case to be attached to the exterior of a house, store, or other structure that it will form a secure receptacle for cans, dishes, &c., either full or empty, and to be conveniently opened by any one authorized, but not to be opened by unauthorized persons except by unlawfully unfastening the same, the safe being so constructed that it can be placed at the right or left of the doorway, as may be desired. This object I attain by the construction shown in the accompanying drawings, in which—

Figure 1 is a view in perspective showing one of my safes closed with a can inside. Fig. 2 is a view in perspective showing one of my safes open, the position of the inclosed can being represented by dotted lines. Fig. 3 is a horizontal section taken through the lock. Fig. 4 is a view enlarged of the lock and its connecting parts, and Fig. 5 shows the lock-plate.

In the drawings, A represents the fixed part of the safe, and B the door, the said door B being attached to the fixed part by hinges E E.

Upon the fixed part of the safe I have a flattened boss P, Fig. 3, which is intended to fit against the flat walls of the structure to which the safe is to be attached by means of screws, one of which is shown at V, Figs. 2 and 3. As this safe is made symmetrical in all respects, its position can be reversed to fit to the right or left, as it may be desired. Turning the safe end for end changes it from a right to a left hand one, thus adapting it to be placed in a right or left hand position in relation to the doorway.

The lock W (shown in detail in Fig. 4) consists of two spring-catches M M, pivoted

on studs N N', and normally held together by the spring S. The spring-catches M are provided at their outer ends with hooks, as shown, adapted to engage with the barbed end of the start L, so that when the door is closed it is securely locked by the engagement of the catches M M with the start L, and it cannot be opened except by inserting the key and unlocking the same.

To prevent the accidental closing and locking of the door, I have two drops K K so suspended from either side of the opening in the face of the lock that one of them will so hang as to cover the opening, and thus prevent the start L from entering the lock; but when it is desired to lock the door the drop covering the opening may be pushed aside, and thus allow the start to enter and to be locked in.

Another and quite essential use of the drops is to hold the door in a partially locked condition. Thus if the door is nearly closed, as represented in Fig. 4, then the hook K' on the drop K will engage with one of the notches of the start L, and thus hold the door nearly closed, but in a condition to be easily opened by simply drawing the engaged drop away from the start.

In Fig. 5 I have shown the plate W', that I use for covering the lock-recess. This plate has a front part W³, so shaped as to fit into a dovetail formed on the edge of the casing, as shown, and a start W², bent at right angles to the main part W', and is adapted to fit into a recess made for it at N². (See Fig. 4.) By forming the plate as above and adapting the lock-recess to receive it; but one screw is required to hold it in place.

This safe may be made of iron or any other suitable material.

In using my safe for milk, for instance, the can is placed within, and the door is so far closed as to cause one of the drops (see Fig. 4) to engage with the start and hold it. Now any person may open the door by pushing the drop away, and having placed a full can in the safe may entirely close the door by causing the start L to enter the lock. Now it cannot be opened except by the use of a

key, which is always retained by the owner of the safe, the person who delivers the milk or other article not having any key.

I claim—

- 5 In a reversible safe, the combination of the recessed lock W in the fixed part A, and the door B, having a barbed start L adapted to engage with the swinging drops K K', said drops K K' being attached to the fixed part of the

safe and so located that one of them, according to which end of the safe is up, will hang over the entrance to the lock and in a position to catch the barbed start, as described, substantially as and for the purpose set forth.

REUBEN H. RICKER.
